UNITED STATES PATENT OFFICE.

DAVID B. WHITEHILL, OF NORTH CLARENDON, PENNSYLVANIA.

BAILING APPARATUS.

SPECIFICATION forming part of Letters Patent No. 638,948, dated December 12, 1899.

Application filed October 25, 1898. Serial No. 694,551. (No model.)

To all whom it may concern:

Be it known that I, DAVID B. WHITEHILL, a citizen of the United States, residing at North Clarendon, in the county of Warren and State 5 of Pennsylvania, have invented a new and useful Bailing Apparatus, of which the following is a specification.

My invention relates to deep-well bailing apparatus, and has for its object to provide a 10 portable apparatus adapted to be operated by horse-power for effectually controlling the elevation and lowering of a bailer, the various movable parts of the apparatus being actuated by means within reach and under the 15 control of a single operator.

Further objects and advantages of this invention will appear in the following description, and the novel features thereof will be particularly pointed out in the appended 20 claims.

In the drawings, Figure 1 is a perspective view of an apparatus constructed in accordance with my invention. Fig. 2 is a vertical section of the same, showing the tilting shaft 25 elevated. Fig. 3 is a plan view, partly in section, to show the means for adjusting the bearing-rolls with relation to the master-gear and the means whereby the strut-supports of the tilting shaft are mounted upon the 30 standards of the frame. Fig. 4 is a partial vertical section at right angles to the plane of Fig. 2 to show the stop-pawl and co-operating means for preventing the backward movement of the bailer during the elevation thereof. Fig. 5 is a detail sectional view of the 35 connection between the rear ends of the bearing-block braces and the standard of the supporting-frame. Fig. 6 is a similar view of the connection between the bearing-block and 40 the front ends of the braces. Fig. 7 is a detail vertical section to show the means of adjustment for the bearing-roller-supporting frame. Fig. 8 is a detail view in perspective of the adjacent extremities of the operating- 45 lever, draw-rod, brake-lever, &c.

Similar reference characters indicate corresponding parts in all the figures of the drawings.

Mounted upon a suitable truck or support- 50 ing-frame 1, which may have supporting-wheels to adapt it for movement to and from the point at which the apparatus is to be

used, is a horizontal master-gear 2, upheld for movement by supporting-rollers 3, mounted upon said truck or supporting-frame, and 55 mounted upon a suitable superstructure rising from said truck or supporting-frame is a tilting drum-shaft 4, having a pinion 5, of which the teeth normally mesh with those of the master-gear, said shaft being mounted 60 for swinging movement toward and from the plane of the master-gear. Said superstructure includes standards 6 and 7, rising from the truck or supporting-frame, and an upright 8, connected by obliquely-disposed 65 braces 9 with the standards 6, and in a bearing 10, formed in said upright, is loosely journaled one trunnion or gudgeon of said drum-shaft. Also connecting the upper ends of the standards 6 is a cross-bar 11, and supported centrally thereon and connecting the same with the upper end of the upright 8 is a frame-bar 12, upon which is fulcrumed an operating-lever 13. This operating-lever is provided at an intermediate point with a rigid 75 depending bifurcated arm 14, pivotally mounted upon the frame-bar 12, and to a bearing-block 15, in which is mounted the other trunnion or gudgeon of the drum-shaft, is connected the extremity of said operating- 80 lever by means of links 16, which are rigid with the bearing-block, whereby in moving the free or handle end of the operating-lever the bearing-block 15 travels in a path approximately concentric with the opposite extremity of the drum-shaft to avoid twisting or straining that trunnion or gudgeon which is mounted in said bearing-block. Also the 85 said links 16 form lateral guides which operate upon opposite sides of the front end of the frame-bar 12 to insure the reciprocation in a 90 truly vertical plane of the bearing-block 15.

Mounted for reciprocatory movement upon the frame-bar 12 is a slide 17, fitted in suitable guides 18 and provided with a stop or enlargement 19, which is adapted when the slide is extended for arrangement in the path of a shoulder 20 on the bearing-block 15, whereby said stop forms a lock to secure the bearing-block in its depressed position against vertical movement, and thus to effectually maintain the teeth of the pinion 5 in operative engagement with the teeth of the master-gear. Connected at an intermediate point with the 95 100

slide is a lever 21, mounted upon the frame and having in connection therewith an operating-rod 22, which terminates at a point near the vertical plane of the rear end of the operating-lever 13, whereby said operating-rod may be grasped with facility by an operator positioned to manipulate said operating-lever.

The drum-shaft 4 carries an armed drum 23, to which is attached one end of a bailer-cable 24, said cable extending at an intermediate point over an elevated direction pulley or sheave 25, supported by a derrick 26 or other equivalent frame, and also arranged upon the drum-shaft, preferably contiguous to the drum, as illustrated in the drawings, is a brake-wheel 27, encircled by a contractible brake-strap 28, with which is connected one arm of a brake-lever 29, also located within reach of an operator positioned to manipulate the lever 13. In the construction illustrated the brake-lever is provided with an intermediate spindle portion, which is mounted in a bearing located upon the upright 8.

To maintain the bearing-block 15 in its proper position with relation to the other elements of the mechanism, I employ pivotal strut-braces 30, stepped at their front ends in seats 31 in opposite sides of said bearing-block, disposed divergently toward their rear ends and stepped at such rear ends in suitable seats 32 in the front sides of the uprights 6, tapered keys 33 being fitted in transverse openings in said strut-braces to bear against the front sides of the uprights, and thus form fulcrums whereby the braces 30 are adapted to swing in vertical planes when the bearing-block is elevated and depressed. Said tapered keys may be adjusted to vary the forward pressure of the braces 30 and are adapted to be secured at the desired adjustment by means of pins 34, engaged with openings in the keys and bearing against the inner surfaces of the braces. To maintain the bearing-block and strut-braces in their proper relative positions, I employ tension-braces 35, extending from said bearing-block rearwardly to and through the standards 6 and fitted at their rear edges with adjusting-nuts 36. Also carried by the drum-shaft is a stop-gear 37, of which the teeth are adapted for engagement with the extremity of a pivotal stop-pawl 38, mounted upon one of the standards 6 and normally held in an elevated or inoperative position by means of a flexible connection 39, consisting of a chain, cable, or equivalent thereof extending over a suitable guide 40 on the cross-bar 11 and adapted for engagement at its rear end with a holding device or catch 41. By disengaging the connection from the catch the stop-pawl may be lowered to arrange its free end in operative relation with the stop-gear, whereby during the elevation of a bailing-bucket the disarrangement of the operating-gears will not cause the dropping of the bailing-bucket for the reason that said pawl will lock the drum-shaft against backward rotation.

Arranged in operative relation with the inner periphery of the rim of the master-gear for holding the latter against vibration upon its seat (formed by the above-described supporting-rolls) are bearing-rolls 42 and 43, which are mounted in pairs upon forwardly and rearwardly adjustable frames, each consisting of upper and lower transverse bars 44 and 45. These adjustable frames, between the extremities of the bars of which are mounted said bearing-rolls, are connected with the standards 6 and 7, respectively, by means of adjusting-bolts 46, and inserted between said frames and the contiguous surfaces of the standards are wedges 47. By loosening the said bolts and suitably adjusting the wedges the frames may be moved either toward or from each other, which adapts the rolls at the extremities of the frames to be moved in pairs in parallel chords of a circle formed by the master-gear. Thus it will be seen that these rolls are adjusted obliquely to a radius and as may be necessary in connection with the rim of the master-gear to insure a closer bearing or reducing the pressure, and thus confine the master-gear operatively in the desired position upon the supporting-rolls. Also connecting the standards 7 and terminally overlapping the rim of the master-gear is a retaining-bar 48 to prevent the vertical displacement of said gear.

The master-gear is adapted to be operated by horse-power, and a simple means whereby such power may be applied to the master-gear consists of a sweep 49, of which one or more may be employed, pivotally mounted at its inner end on the outer face of the master-gear for vertical swinging movement, provided at its outer end with a suitable clevis 50 for the whiffletree to which the power is applied and held in the desired position against forward displacement under strain by means of a tension rod or brace 51, while the whiffletree supports the outer end vertically, yet permits it to yield as may be necessary to conform with the height of the animals hitched thereto.

In operation the tilting shaft, by which the pinion 5 is carried, may be elevated to disengage said pinion from the master-gear to allow backward rotation of the drum, and such backward rotation may be controlled as to speed by means of the brake mechanism hereinbefore described. Also when the tilting shaft is depressed and the receiving-gear or pinion 5 is in operative engagement with the driving or master gear 2 the slide 17 may be moved forward to lock the forward bearing of said shaft in its depressed position, and during the elevation of a bailing-bucket the stop-pawl 38 may be released to allow its free end to drop into operative relation with the stop-gear 37, whereby accidental backward rotation of the drum-shaft is prevented.

It will be seen from the foregoing description that I have provided a simple, comparatively inexpensive, and efficient apparatus for bailing purposes which may be moved by

horse-power to the point of use over a well to be bailed and of which the operating parts may be controlled by a single attendant located within reach of the operating-lever 13, 5 and also of the operating-rod 22 and brake-lever 29, and it will be understood, furthermore, that various changes in the form, proportion, and the minor details of construction may be resorted to without departing 10 from the spirit or sacrificing any of the advantages of the invention.

In the construction illustrated the derrick consists of a plurality of timbers separate from the supporting-frame of the operating 15 mechanism, suitably connected at their upper ends and adapted to rest at their lower ends upon or be embedded in the soil, said lower ends being spaced from the supporting-frame or truck of the mechanism at such a 20 distance as to allow the animals by which power is communicated to the master-gear to move under the derrick-beams or within the circle described by the lower ends of said beams. This construction provides for lightness, and hence increased portability, of the operating mechanism, while giving the operator 25 the necessary control of the various movable elements of the machine. Furthermore, it will be observed that by the use of an annular master-gear having its center wholly open I 30 am enabled to make it of a sufficiently large diameter to obtain a firm and steady bearing upon the supporting-framework and at the same time allow the bailer-cable to operate therethrough, and thus economize the space required in which to operate the machine. The drum also is located at the longitudinal center of the framework, and hence the upward strain applied thereto in the operation of elevating the bailer-bucket is approximately 35 in alinement with the center of the structure. 40

In operation a bailer-bucket of the ordinary construction is lowered by means of the cable and operating devices into a well, is 45 filled with the sand or other material contained in the well, and is withdrawn therefrom in order to put the well into condition for further drilling or for pumping. The operation of bailing a well is so well known in 50 the art as to require no more specific statement.

Having described my invention, what I claim is—

1. A deep-well bailing apparatus having a 55 frame provided with supporting-rolls, a rotatable annular master-gear horizontally disposed upon said supporting-rolls, a drum-shaft having a pinion meshing with the master-gear, supporting-frames having rolls in 60 their opposite ends arranged in contact with the inner surface of the rim of the master-gear, means for adjusting said frames longitudinally of the machine to change the bearing-contact of the rolls in the ends thereof 65 relatively to the master-gear, a drum on the said drum-shaft, and a bailing-rope adapted to be wound upon or from the said drum.

2. A deep-well bailing apparatus having a supporting-frame provided with supporting-rolls, an annular master-gear horizontally disposed upon said supporting-rolls, means for communicating rotary motion to said master-gear, a drum-shaft having a pinion meshing with the master-gear, bearing-rolls arranged in contact with the inner surface of the rim 70 of the master-gear, frames for supporting said bearing-rolls, adjusting-bolts for securing the bearing-roll-supporting frames to fixed parts of the structure, and wedges interposed between said bearing-roll-supporting frames 75 and fixed parts of the structure, said bolts and wedges adapted to move said frames to and from each other to vary the positions of the bearing-rolls with relation to the rim of the master-gear, in combination with a derrick, 80 a drum, and a bailing-rope depending through said master-gear, substantially as specified.

3. A deep-well bailing apparatus having a supporting-frame, a horizontally-disposed 90 master-gear mounted upon said frame for rotary movement, a drum-shaft mounted at its rear end in a fixed bearing, a movable bearing-block for the opposite end of the drum-shaft, movable supports for said bearing-block whereby the latter may be swung in a path concentric with the fixed bearing of the drum-shaft, a pinion carried by the movable 95 end of the drum-shaft for engagement with the master-gear, means for holding the pinion in operative engagement with the master-gear, a drum, and a bailing-rope depending through said master-gear, substantially as specified.

4. A deep-well bailing apparatus having a 105 framework and a horizontally-disposed master-gear adapted for rotary movement, in combination with an operating-lever having a laterally-offset fulcrum-point, a drum-shaft 110 mounted at one end in a fixed bearing for tilting movement and provided adjacent to the other end with a pinion to mesh with said master-gear, a movable bearing-block in which the pinion-carrying end of the drum-shaft is mounted, links connecting said bearing-block 115 with said operating-lever, a drum, and a bailing-rope depending through said master-gear, substantially as specified.

5. In a deep-well bailing apparatus, the combination with a supporting-framework 120 having standards, and a master-gear mounted upon said framework for rotary movement, of a drum-shaft mounted at one end in a fixed bearing for tilting movement and provided at the other end with a pinion to mesh with said 125 master-gear, a movable bearing-block in which the pinion-carrying end of said drum-shaft is mounted, means for moving said bearing-block toward and from the plane of the master-gear, strut-braces extending from the 130 bearing-block to said standards of the framework, and terminally stepped, respectively, in said bearing-block and standards, tension-braces connecting the bearing-block with

4
said standards, a drum, and a bailing-rope, substantially as specified.

6. In a deep-well bailing apparatus, the combination with a supporting-framework having standards, and a master-gear mounted upon said framework for rotary movement, of a tilting drum-shaft mounted at one end in a fixed bearing, and provided at the other end with a pinion to mesh with the master-gear, a movable bearing-block in which the pinion-carrying end of the drum-shaft is mounted, means for moving the bearing-block toward and from the plane of the master-gear, rearwardly-divergent strut-braces stepped at their front ends in seats in the bearing-block, tapered keys arranged transversely in said strut-braces near their rear ends and bearing against said standards, means for securing said keys at the desired adjustment, adjustable tension-braces connecting the bearing-block with the standards, a drum, and a bailing-rope, substantially as specified.

7. In a deep-well bailing apparatus, the combination with a supporting-framework having standards, and a master-gear mounted upon said framework for rotary movement, of a tilting drum-shaft mounted at one end in a fixed bearing, and provided at the other end with a pinion to mesh with the master-gear, a movable bearing-block in which the pinion-carrying end of the drum-shaft is mounted, means for moving the bearing-block toward and from the plane of the master-gear, rearwardly-divergent strut-braces stepped at their front ends in seats in the bearing-block, tapered keys arranged transversely in said strut-braces near their rear ends and bearing against said standards, securing-pins engaging openings in said keys for securing them at the desired adjustment, adjustable tension-braces connecting the bearing-block with the standards, a drum, and a bailing-rope, substantially as specified.

8. In a deep-well bailing apparatus, the combination with a supporting-framework having standards, and a master-gear mounted upon said framework for rotary movement, of a tilting drum-shaft mounted at one end in a fixed bearing in said framework and provided at the other end with a pinion to mesh with the master-gear, a bearing-block for the pinion-carrying end of said shaft movable toward and from the plane of the master-gear, an operating-lever mounted upon the framework and having an offset fulcrum-point, connections between said operating-lever and the bearing-block, an adjustable stop adapted for arrangement in the path of a shoulder on said bearing-block to hold the latter in position to maintain the pinion of the drum-shaft in en-

gagement with the master-gear, a drum, and a bailing-rope, substantially as specified.

9. In a deep-well bailing apparatus, the combination of a supporting-frame having front and rear standards, and a forwardly-extending frame-bar connecting the rear standard with and projecting in front of a cross-bar connecting the front standards, a master-gear horizontally mounted upon the supporting-frame, a drum-shaft having its rear end mounted in a bearing in the rear standard and provided at its front end with a pinion to mesh with the master-gear, an operating-lever having a bifurcated arm fulcrumed upon said frame-bar, said lever terminating near the rear end of said frame-bar, a bearing-block in which the front end of the drum-shaft is mounted, and which is movable toward and from the plane of the master-gear to cause the engagement and disengagement of said pinion with the master-gear, tension-braces connecting the bearing-block with said front standards, links connecting the bearing-block with the front end of the operating-lever, locking devices for the bearing-block including a slide, a stop on the slide for arrangement in the path of a shoulder on the bearing-block, and means, for operating the slide, including an operating-rod terminating near the rear end of said frame-bar, brake mechanism including a brake-lever located near the rear standard, a drum operated by said drum-shaft, and a bailing-rope, substantially as specified.

10. In a deep-well bailing apparatus, the combination with a derrick having its supporting-beams spaced apart at their lower ends, of a separate supporting-framework arranged within the space between the lower ends of the derrick members, a drum mounted upon said framework and having attached thereto a cable extending over a guide supported by the derrick, an annular centrally-open master-gear also mounted upon said framework and operatively connected with the drum, the bailer-cable being adapted to pass through the space bounded by the master-gear, and horse-attaching means carried by the master-gear whereby the attached animals are adapted to traverse a circular path within the space between the lower ends of the derrick members, substantially as specified.

In testimony that I claim the foregoing as my own I have hereto affixed my signature in the presence of two witnesses.
